Primary Examiner — Catherine Tuttle

(57) **CLAIM**

The ornamental design for an instructional soccer ball, as shown.

DESCRIPTION

FIG. 1 is a front view of the instructional soccer ball showing my design.

FIG. 2 is the rear view thereof;

FIG. 3 is the left side view thereof;

FIG. 4 is the right side view thereof;

FIG. 5 is the top view thereof; and,

FIG. 6 is the bottom view thereof.
